US00D788861S

(12) **United States Design Patent** (10) **Patent No.:** **US D788,861 S**
Campanaro et al. (45) **Date of Patent:** **** Jun. 6, 2017**

(54) **ROWING EXERCISE MACHINE**

(71) Applicant: **Total Gym Global Corp.**, San Diego, CA (US)

(72) Inventors: **Thomas J. Campanaro**, Rancho Santa Fe, CA (US); **Jesse Thomas Campanaro**, San Diego, CA (US); **Dan McCutcheon**, San Diego, CA (US)

(73) Assignee: **Total Gym Global Corp.**, San Diego, CA (US)

(**) Term: **15 Years**

(21) Appl. No.: **29/542,858**

(22) Filed: **Oct. 19, 2015**

(51) **LOC (10) Cl.** **21-02**

(52) **U.S. Cl.**

USPC **D21/674**

(58) **Field of Classification Search**

(57) **CLAIM**

The ornamental design for a rowing exercise machine, as shown and described.

DESCRIPTION

FIG. 1 is a perspective view of the rowing exercise machine; FIG. 2 is a right side elevational view of the rowing exercise machine;

FIG. 3 is a left side elevational view of the rowing exercise machine;

FIG. 4 is a front elevational view of the rowing exercise machine, the rear elevational view being a mirror image thereof;

FIG. 5 is a top plan view of the rowing exercise machine; and,

(Continued)

FIG. 6 is a bottom plan view of the rowing exercise machine. Any broken lines shown in FIGS. 1-6 are included for the purpose of illustrating environmental elements only and form no part of the claimed design.

1 Claim, 4 Drawing Sheets
